UNITED STATES PATENT OFFICE.

BERNE NADALL, OF CHICAGO, ILLINOIS, ASSIGNOR TO THE LINOTYPE COMPANY, LIMITED, OF LONDON, ENGLAND.

DESIGN FOR A FONT OF UPPER-CASE PRINTING-TYPE.

SPECIFICATION forming part of Design No. 36,018, dated August 19, 1902.

Application filed July 17, 1902. Serial No. 116,007. Term of patent 14 years.

To all whom it may concern:

Be it known that I, BERNE NADALL, a citizen of the United States, residing at Chicago, in the county of Cook and State of Illinois, have invented and produced a new, original, and ornamental Design for a Font of Upper-Case Printing-Type, of which the following is a specification.

My new and original design for a font of upper-case printing-type is illustrated in the accompanying drawing, referring to which some of the distinguishing features or characteristics of the font members will be described.

15 A feature common to all of the type composing the font is that the several lines are relatively broad or heavy.

The right-hand line of the letter A is a compound curve extending upwardly and toward the left from the enlarged and horizontally-arranged base or foot at its lower end. The left-hand line of said letter is curved throughout its length and gradually increases in width from its upper to its lower end. Said lower 25 end of the left-hand line is connected with the right-hand line by a transverse line that is inclined upwardly from its left-hand end. The connected lower ends of the left-hand line and said transverse or connecting line 30 extend some distance below the horizontal plane of the foot or base of the right-hand line of the letter.

The left-hand substantially perpendicular lines of the letters B and D are provided at 35 both terminals with projections extending toward the left, forming a slightly concave face or side at the left of said lines. The intermediate transverse line of the letter B is inclined, and the lower line of the letter D 40 is concaved on its outer side and decreases in thickness from the left-hand line of the letter toward its point of connection with the right-hand line thereof. This latter line has such a curve that the space within the letter 45 gradually increases in width from its upper to its lower end. Said right-hand curved line of the letter D gradually increases in thickness from its connection with the left-hand line of said letter toward the lower line 50 of the letter.

The upper terminals of the left-hand lines

of the letters E and F extend above the upper laterally-projecting lines thereof and are deflected slightly toward the left. The lower ends of said lines are provided with enlarged 55 feet or bases. The upper and lower laterally-projecting lines of the letter E and the corresponding upper line of the letter F are curved and gradually increase in width toward their free ends. The intermediate horizontal line 60 of the letter E and the lower laterally-projecting line of the letter F are relatively lighter or thinner than the other lines of said letters, and at their free ends both terminate in enlargements which project below said 65 lines to a greater extent than they extend above the same, the terminal of the said line of the letter F, being more pronounced than that of the corresponding line of the letter E.

The letter G is formed by a curved or bowed 70 line having its lower end terminating in a short substantially perpendicular line, from the free upper end of which a compound-curved line extends inwardly or toward the left. The curve forming the body of said 75 letter is reduced in width near its connection with the aforesaid perpendicular, forming a short, straight, inclined section, and the lateral projection at the upper end of said perpendicular increases gradually in 80 width toward its free end.

Both the left and right hand lines of the letter H are curved slightly longitudinally, so that they are separated to a greater extent 85 at their terminals than at their middle portions, and said lines are connected by two parallel horizontal lines.

The letter I consists of a single line having enlarged terminals, the face of the lower one being horizontal, while that of the upper one 90 is inclined.

The upper end of the main line of the letter J is deflected slightly toward the right, and the loop or curve at the lower end of said line is a relatively small or close one, and the line 95 forming it is considerably thinner than that forming the stem or body of the letter.

The upper inclined line of the letter K is thinner than the lower inclined line, so that the distance between the free end of said line 100 and the left-hand perpendicular line of the letter is greater than the distance between

2
said perpendicular and the free end of the lower inclined line.

Both ends of the perpendicular of the letter L are deflected slightly toward the left. The 5 lower line of said letter has its free end deflected upwardly slightly, and it gradually increases in width from its connection with the perpendicular toward said deflected free end. The face of said terminal is inclined to the 10 horizontal and extends substantially at right angles to the sides of the deflected portion thereof.

The left-hand lines of both sections of the letter M are relatively thinner than those of 15 the right-hand lines thereof, and said left-hand line of the right-hand section is curved. Both of the upper lines of said figure are provided with enlarged feet or bases and have slightly - projecting portions at their upper 20 ends.

Both ends of the perpendicular of the letter R are deflected toward the left. The curve 25 at the right-hand side of said perpendicular extends substantially the entire length of the letter, decreasing in thickness from an intermediate section and being of such form that the space between it and said perpendicular is substantially the shape of a heart arranged in an inclined position. Near its lower end 30 the curve is provided with a laterally-projecting inclined line, the left-hand face of which is slightly curved and which has a large projecting foot or lower terminal.

The upper end of the curved line of the let-

ter S is connected with the intermediate or 35 body curve by a slight substantially perpendicular line.

Both terminals of the letter U are deflected somewhat toward the left, and the right-hand line of said letter is thinner than that at the 40 left.

The letter V is formed by two curved lines, the left-hand one of which has an enlarged or expanded upper terminal, the face of which is substantially horizontal. The free end of 45 the right-hand line of this letter is deflected somewhat toward the left and is inclined, its highest point only reaching the horizontal plane of the free end of the left-hand line.

The laterally-projecting lines of the letter 50 Z are connected with the main inclined line of said letter at points inside of the ends thereof, and said laterally-projecting lines are curved and increase in thickness from said inclined line toward their free ends. 55

Having thus described my invention, what is claimed, and desired to be secured by Letters Patent, is—

The ornamental design for a font of upper-case printing-type substantially as herein 60 shown and described.

In testimony whereof I affix my signature in presence of two witnesses.

BERNE NADALL.
